UNITED STATES PATENT OFFICE

LAWRENCE A. MERK, OF PITTSBURGH, PENNSYLVANIA, ASSIGNOR TO RAILWAY MAINTENANCE CORPORATION, OF ASPINWALL, PENNSYLVANIA, A CORPORATION OF PENNSYLVANIA

LUBRICATOR

Application filed April 26, 1929. Serial No. 358,265.

This invention relates to lubricators and more particularly to lubricators of the overflow type wherein a lubricant-applying reservoir is provided which has an opening 5 through which lubricant is adapted to overflow to the point of application.

The invention is particularly applicable for lubricating railroad track adjacent a curve, although the invention is also useful 10 for many other purposes. It will be described for purposes of illustration as applied to a lubricating device for applying lubricant to railroad track.

In my copending application Serial No. 15 329,098, filed December 29, 1928, there are disclosed several lubricating devices adapted for applying lubricant to railroad track and to the flanges of car wheels passing thereover. Such devices all depend for their action 20 upon the positive forcing of the lubricant through a lubricant-applying conduit by means of a pump or plunger operated through suitable lever mechanism by the wheels of a moving car. A lubricant-applying means is used which comprises an arm 25 adapted to be positioned directly between the rail head and the flanges of wheels passing thereover.

In order to insure sufficient spacing of the 30 wheel flanges from the rail head so that the lubricant-applying means may be disposed therebetween, it is necessary to provide a guard rail at the opposite side of the track to pull the car away from the rail to which 35 the lubricant is to be applied. Furthermore, in devices of the type disclosed in my said co-pending application, it is necessary in order to supply the lubricant to the point of 40 application, to provide a system of pumps and levers for forcing the lubricant through the lubricant-applying conduit to the point of application.

The present invention is to be distinguished 45 from that of my said copending applica-

tion by reason of the provision inter alia of means for applying lubricant to the point of application which does not require the use of a guard rail or a pump or operating means therefor to positively force the lubricant 50 through a lubricant-applying conduit.

I provide a lubricator, comprising a lubricant tank, a lubricant applying reservoir having a connection extending within the tank and below the surface of lubricant contained in the tank, said connection being movable in relation to the lubricant in the tank to replenish the reservoir, means operable by a moving car for causing such movement, and an outlet from the reservoir for 60 applying lubricant. I further provide a lubricator, comprising a lubricant tank, lubricant applying means cooperating with the tank and adapted for movement in a generally vertical plane to apply lubricant to the 65 side of a rail head, and spring means urging the lubricant applying means toward the rail head.

Other objects and advantages of the invention will become apparent as the following 70 description of a present preferred embodiment thereof proceeds.

In the accompanying drawings I have shown a present preferred embodiment of the 75 invention, wherein

Figure 1 is a top plan view of a lubricator, showing it applied to a rail,

Figure 2 is a cross-section on the line II—II of Fig. 1,

Figure 3 is a cross-section on the line 80 III—III of Fig. 1, and

Figure 4 is a view similar to Fig. 3 but showing the lubricator in a different operating position.

Referring more particularly to the drawings, reference numeral 2 designates a rail having a head 3, a web 4 and a base 5. The rail 2 forms one of a pair of rails of a track, and disposed between the two rails, but adjacent the inner side of the rail 2, is a lubri- 85 90

cant tank 6. The tank 6 is of elongated shape, being adapted to lie against and parallel to the rail 2. It comprises an inner wall 7 which terminates at 8 and is adapted to 5 underlie and press against the head 3 of the rail. The tank 6 has a central portion 9 of greater depth than the remainder of the tank, for a purpose to be presently described. It 10 is provided at the portion 9 with a removable drain plug 10.

As shown in Figs. 3 and 4, the portion of the tank 6 above the deep portion 9 extends laterally over the base 5 of the rail so as to permit the upper extremity 8 of the wall 7 15 to lie against the rail head as above described, and also to increase the capacity of the tank. A packing material 11, such as strips of wood, may be interposed between the web 4 of the rail and the wall 7 of the tank so as to 20 maintain the tank in proper relationship with the rail. A bolt 12 passes through the web of the rail, the packing material 11 and the opposite walls of the tank 6, whereby to maintain the tank in place with respect to 25 the rail. The tank is provided on its outer surface with threaded bosses 13 receiving the extremities of the bolts 12. The bolts may be provided with suitable washers 14 adapted to lie against the web of the rail, and may 30 then be tightened to draw the tank firmly against the packing material to maintain the wall extremity 8 in permanent contact with the underside of the rail head.

Loosely mounted on the portion of each of 35 the bolts 12 which lies within the tank 6 is a bell crank lever 15, one extremity 16 of which is adapted to cooperate with an adjustable stop 17 to limit the pivotal movement of the lever about the bolt 12. Pivotally connected with the respective bell crank 40 levers 15 and 18 through bosses 19 is a lubricant-applying reservoir designated generally by reference numeral 20. This reservoir comprises an elongated portion 21 adapted to 45 lie against the side of the rail head and an offset portion 22 communicating with the portion 21. The offset portion 22 lies above the portion 9 of the tank 6. This portion is provided with a downwardly extending conduit 23 which enters the bottom of the portion 22 and extends upwardly therein for an appreciable distance. The conduit 23 is provided at its lower extremity with an enlargement 50 24 having a circular valve seat 25 and containing a ball check valve 26.

The elongated portion 21 of the reservoir 55 20 is provided at its under surface with projections 27 which lie substantially above similar projections 28 on the inner surface 60 of the bottom of the tank 6. The respective projections 27 and 28 maintain in place coil springs 29 which, under compression, tend to raise the reservoir about the respective pivots 12, the movement thereof being limited by 65 contact between the extremities 16 of the

respective bell crank levers and the adjustable stops 17. The portion 21 of the reservoir is provided with a longitudinal slot or overflow opening 30 adjacent its upper surface and through which lubricant is adapted to pass to be applied to the inner surface of the rail head. The portion of the reservoir adjacent the overflow opening 30 is adapted at all times to bear against the inner surface of the rail head. To this end, 70 coil springs 31 are disposed about the bolts 12 between the outer wall of the tank 6 and the respective bell crank levers 15 so that such levers and the reservoir which is carried by them are always resiliently urged 75 toward and into contact with the rail head. This provision is of considerable advantage when rails having tapered heads are to be lubricated, as in such cases a lateral as well as a vertical movement of the reservoir will 80 occur. The reservoir is reinforced at its upper portion 32 adjacent the rail head so as to be adapted to be engaged by flanges 33 of 85 wheels riding upon the rail 2.

The top of the offset portion 22 of the reservoir extends above the top portion 32 of the elongated part of the reservoir. This forms an air dome effective for confining air 90 so that the same may be slightly compressed during operation of the lubricator, the compression later being effective for positively actuating the lubricant toward the point of application, as will be presently described.

The operation of the lubricator is as follows. The tank 6 is filled with lubricant to a level such as that shown in Figs. 3 and 4. When a car passes over the track the wheel flanges 33 engage and depress the reservoir 20, causing downward pivotal movement thereof about the axes of the bolts 12 and 100 against the compression of the coil springs 29. On account of the speed with which the car moves the depression of the reservoir is rapid. The conduit 23 therefore moves rapidly through the body of lubricant in the tank 6, causing the ball valve 26 to be raised from its seat 25 to admit lubricant into the chamber 24. Such action will take place 105 because the body of lubricant in the tank is substantially at rest and by reason of the rapid movement of the conduit through the body of lubricant, the lubricant will not permit passage of the conduit through it without sufficient resistance to unseat the valve 26, thereby admitting lubricant to the conduit 23. After the car wheel passes over the reservoir the springs 29 are effective for raising the reservoir to its normal position as determined by the adjustable stops 17. Upon the upward movement of the reservoir the 110 valve 26 seats in its seat 25, thereby preventing back-flow of lubricant from the reservoir into the tank. The action of the lubricant is so rapid, particularly when a number of fast moving cars pass over it in succession, that 115 120 125 130

air will be compressed within the air dome in the reservoir. The lubricant in the reservoir is adapted to overflow through the opening 30 against the rail head. The compressed air in the air dome assists in positively delivering the lubricant so that the same will be distributed throughout the entire length of the portion 21 and lubricate the rail throughout a substantial portion of its length. When no wheel is passing over the lubricator the lubricant in the reservoir will overflow through the opening 30 until its level reaches the level of the bottom of such opening, whereupon overflow will cease until another wheel passes over the lubricator, depressing the reservoir and causing more lubricant from the tank 6 to pass the valve 26 and into the conduit 23, whereupon such lubricant is raised into the reservoir and in turn flows out through the overflow opening.

The lubricant which is applied to the rail head is for the most part taken up by the wheel flanges and thereby spread along the rail for a considerable distance. Any excess lubricant not taken up by the wheel flanges flows down the side of the rail head and back into the tank 6, as will be seen from Figs. 3 and 4. The extremities of the elongated portion 21 of the reservoir are tapered downwardly, as shown in Fig. 2, in order that too great a shock may not be imparted to the lubricator upon the impact of a wheel thereagainst. Although the movement of the lever is rapid, nevertheless it is considerably more gradual by reason of the tapered extremities than it would be were the full effect of each wheel to be felt instantaneously.

The provision of the air dome in the reservoir is not essential to the operation of the device, but is preferred to assist in delivering the lubricant more effectively throughout the entire length of the reservoir so that it flows out through substantially every portion of the overflow opening 30. The number of conduits 23 and the length of the reservoir may be varied in accordance with operating conditions. The tank may be of sufficient length to accommodate more than one reservoir, although it is found to be more satisfactory when only one reservoir is used per tank.

While I have shown and described a present preferred embodiment of the invention, it is to be distinctly understood that the same is not limited thereto but may be otherwise variously embodied within the scope of the following claims.

I claim:—

1. A lubricator, comprising a tank adapted to contain lubricant, a reservoir having a portion within the tank forming a conduit between the tank and reservoir, a check valve in the conduit, the reservoir being movable in relation to the tank to replenish the reservoir, the check valve preventing backflow into

the tank, means operable by a moving car for causing movement of the reservoir, and an outlet from the reservoir for applying lubricant, the reservoir being adapted to contain a substantial quantity of standing lubricant, the outlet having a substantially horizontal lower surface over which the standing lubricant may easily flow. 70

2. A lubricator, comprising a lubricant supply, lubricant applying means comprising a reservoir having an outlet, said reservoir being connected with the supply and adapted to move up and down with said outlet in contact with the side of a rail head, the lubricant applying reservoir being also resiliently urged toward the rail head so as to at all times remain in contact therewith. 75

3. A lubricator, comprising a lubricant tank, lubricant applying means comprising a reservoir having an outlet, said reservoir cooperating with the tank and adapted for movement in a generally vertical plane to apply lubricant through said outlet to the side of a rail head, and spring means urging the lubricant applying means toward the rail 80 head. 85

4. A lubricator, comprising a tank, a lubricant applying reservoir in communication with the tank, means for causing lubricant to pass from the tank to the reservoir, means for preventing backflow into the tank, and an air trap in the reservoir wherein air is adapted to be compressed as lubricant passes from the tank to the reservoir, the compressed air being effective for expelling the lubricant 90 from the reservoir. 95

5. A lubricator, comprising a tank, a lubricant applying reservoir having a portion extending into the tank through which lubricant is adapted to pass from the tank to the reservoir, an air trap in the reservoir in which air is adapted to be compressed as lubricant passes from the tank to the reservoir, and overflow means in the reservoir through which lubricant is adapted to be expelled. 105 110

6. A lubricator, comprising a lubricant supply, lubricant applying means in communication with the supply, pivots on which the applying means is loosely mounted for movement in a generally vertical plane to apply lubricant to the side of a rail head, and resilient means acting generally axially of the pivots for urging the applying means against the rail head. 115 120

7. A lubricator, comprising a tank adapted to lie along a rail, fastening means connected with the tank for fastening the tank to the rail, lubricant applying means swingably pivoted on the fastening means, and springs urging the applying means generally axially of the fastening means against the rail head. 125

8. A lubricator, comprising a lubricant supply, an overflow device for positively delivering a quantity of lubricant to a rail of 130

a track, and operating means for causing delivery of lubricant by the over-flow device, such operating means being adapted for actuation by a wheel running on the track and 5 being swingable in a plane generally parallel to the track.

9. A lubricator, comprising a lubricant supply and lubricant applying means in communication with the supply and adapted to 10 apply lubricant to a rail of a track, such lubricant applying means being adapted for actuation by a wheel running on the track and being swingable in a plane generally parallel to the track.

15. In testimony whereof I have hereunto set my hand.

LAWRENCE A. MERK.
